ELECTRICAL CONDUCTOR

Ewart S. Taylerson, Pittsburgh, Pa., assignor to
Carnegie-Illinois Steel Corporation, a corpora-
tion of New Jersey

Application April 28, 1939, Serial No. 270,706

4 Claims. (Cl. 173—324)

This invention relates to electrical conductors, and more particularly to electrical conductors which are flexibly or otherwise resiliently mounted so as to insure an unbroken continuous electrical contact with a rotary member.

An object of the present invention is to provide an electrical conductor which will at all times uniformly contact the ends of a rotary member, such as a conductor roll.

Another object is the provision of a plurality of electrical conductor brushes, each of which is capable of following any lateral motion of the rotary members.

A still further object of the present invention resides in pivotally mounting the brushes upon a supporting plate so as to compensate for unequal wear of the brush contact points.

A further object resides in providing a uniform pressure on each brush in each group, so that they will uniformly contact the rotary member at all times.

Other objects and advantages will become apparent as the description proceeds and reference is had to the accompanying drawings, in which:

Figure 1 is a side elevation, partly in section of the present invention;

Figure 2 is a sectional elevation on line II—II of Figure 1;

Figure 3 is a detailed section of one of the brush assemblies;

Figure 4 is an enlarged detailed showing of one of the brushes; and

Figure 5 is a detailed section of a modified form of the adjusting means for the brush.

In the drawings, there is shown a supporting member 2 having secured thereto, in any conventional manner, bearing brackets 3. Each of these brackets carries bearings 4 of conventional design for supporting a shaft 5, upon which is mounted a conductor roll 6. Secured to each end of said conductor roll 6 is a metal plate, hereinafter termed a collector plate 7. Bearing against said collector plate 7 are several groups of contactors, hereinafter termed brush assemblies 8. Each brush assembly 8 includes a brush holder member 9, provided with two divergent faces 10 and a central opening 12 formed therein. Attached to each of the divergent faces 10 are contact members 14, each of which comprises several thin metallic strips 15. The metal or alloy chosen for the purpose should possess low electrical resistivity and high resiliency. As an example of such an alloy, phosphor bronze may be used. In order to provide maximum resiliency and flexibility to the brush assembly 8, the

thin metallic strips 15 have interposed between them, at their point of attachment to the brush holder member 9, short metallic separators 16. Such a laminar construction also provides an air space between the free ends of each of the thin metal strips 15. Such air spaces are desirable to prevent heating of the contact members when carrying heavy electric currents. Further, each of the thin metal strips 15 comprising a given contact member 14, varies in length, the outermost strip being the longest with the length of the other strips decreasing, the strip adjacent the divergent face 10 being the shortest. In this manner each metallic strip 15 will contact the collector plate 7 with equal facility.

Since the two contact members 14 of an individual brush assembly 8 diverge from its brush holder member 9, a triangular shaped arch is formed. This construction provides a resilient metal brush, the action of which can be likened to an elliptical spring, i. e. any force which tends to flatten the arch if a spring is resisted by a reaction force set up within the material forming the "leaves" of the spring.

Positioned between the bearing 4 and each collector plate 7, is a metal plate 17, which serves to support the brush assemblies 8. The plate 17 is provided with a plurality of cut-out portions 18 within which is centrally disposed a pin 19. The brush assemblies 8 are mounted on said pin 19 and are secured thereon in any convenient manner, for example by the check plate 20. The means used for securing the assemblies 8 to the pin 19 should, however, be such that the assemblies 8 are free to swing on pins 19 through a small arc. This is necessary to permit any assembly 8 to automatically adjust its position to compensate for any unequal wear of its contact members 14, and thereby maintain equal contact between both of said contact members and the collector plate 7 at all times.

Fixedly secured to the brush holder member 9 is a flexible lead 21, capable of conducting the electric current between the brush assemblies 8 and the plate 17. The flexibility of the lead 21 is necessary to permit the free movement of the assemblies 8, hereinabove described.

Secured to each plate 17, in any conventional manner, are two terminals 22, which are connected to main feeding bus-bars 23, through suitable flexible lead wires 24. The plate 17 is also provided with a central opening 25, through which the shaft 5 of the conductor roll 6 passes. The diameter of the opening is such that there

is a clearance between it and the shaft 5 so as to prevent contact of said shaft and plate 17. On those surfaces of the plate 17 which face the bearings 4 are sockets 26, which receive rods 28, the blunt ends of which bear against the bottoms of the sockets. The threaded ends of the rods 28, pass through clearance holes 29, formed in the bearing bracket 3. The rods 28 are provided with nuts 30, which bear against that surface of the bracket 3 facing the plate 17. By such a construction, the brush assemblies 8 are firmly pressed against the collector plate 7 and the pressure can be regulated by adjusting the nuts 30 on the rods 28. This, combined with the resilient construction of the brush assemblies, produces a spring loaded metallic conductor capable of transferring electric current between a stationary and a rotating conductor. Such a conductor is capable of following any lateral movement of the rotating member such as might result from the misalignment of the collector plate or from deflection of the conductor roll under mechanical load. It is also capable of taking care of any wear of the brush members, whether such wear is uniform or non-uniform. This action insures at all times a constant and uniform contact of all the brush members with the collector plate of the rotating conductor.

As an alternate method of obtaining the above stated results, the plate 17 may itself be resiliently mounted in which case stiffer brushes may be used if desired. This is accomplished by substituting stud bolts 31 for the rods 28. Such stud bolts are rigidly secured to the plate 17, their free ends pass through the clearance holes 29, and they are provided with springs 32, which are positioned between the plate 17 and the bracket 3 and around each of said stud bolts. In this manner the plate 17 is spring loaded and presses the brushes mounted thereon against the collector plate 7 of the conductor roll. This construction also insures constant and uniform contact of all the brushes with the collector plate at all times.

While I have shown and described specific embodiments of the present invention, it will be seen that I do not wish to be limited exactly thereto,

since various modifications may be made without departing from the scope of the invention, as defined by the following claims.

I claim:

1. An electrical conductor comprising a resiliently mounted plate, a plurality of brush holders pivotally mounted thereon, and a laminated brush carried by each of said brush holders and providing portions extending divergently therefrom, the outer ends of the laminae of said brushes terminating in a plane which is substantially parallel to that of the said resiliently mounted plate.
2. An electrical conductor comprising a resiliently mounted plate, a plurality of brush holders pivotally mounted thereon, and a laminated brush carried by each of said brush holders and providing portions extending divergently therefrom, the outer ends of the laminae of said brushes terminating in a plane which is substantially parallel to that of the said resiliently mounted plate, the pivotal axes of said brush holders extending in substantially the same general direction as the surface of said resiliently mounted plate from which the brushes extend.
3. An electrical conductor comprising a support, and a resilient V-shaped laminated brush pivotally mounted on said support, the outer ends of the laminae of the divergently extending portions of said resilient V-shaped laminated brush terminating in a common plane, the pivotal axis of said brush extending substantially parallel to said plane and at substantially right-angles to a plane common to the divergently extending portions thereof.
4. An electrical conductor comprising a resilient support, and a resilient V-shaped laminated brush pivotally mounted on said support, the outer ends of the laminae of the divergently extending portions of said resilient V-shaped laminated brush terminating in a common plane, the pivotal axis of said brush extending substantially parallel to said plane and at substantial right-angles to a plane common to the divergently extending portions thereof.

EWART S. TAYLERSON.
